UNITED STATES PATENT OFFICE.

EVAN OWEN WILLIAMS, OF PARKSTONE, ENGLAND, ASSIGNOR TO WILLIAMS FOREIGN PATENTS LIMITED, OF LONDON, ENGLAND.

REINFORCED-CONCRETE SHIP.

1,316,659.

Specification of Letters Patent. Patented Sept. 23, 1919.

Application filed May 13, 1918. Serial No. 234,207.

To all whom it may concern:

Be it known that I, EVAN OWEN WILLIAMS, a subject of the King of Great Britain, residing at "Shaston," Ardmore Road, 5 Parkstone, Dorsetshire, England, have invented certain new and useful Improvements in Reinforced-Concrete Ships, of which the following is a specification.

This invention relates to improvements in ships, barges, floating structures and the like, and it has for its object to provide structures of this kind which have the advantage of increased strength combined with lighter weight and greater carrying capacity.

Hitherto it has been usual to construct the walls of reinforced concrete structures of the above kind of solid reinforced concrete slabs stiffened on either or both sides with concrete ribs and to concentrate the metal 15 reinforcement in particular parts of the ribs and at or near their junction with the body of the slab.

Now, according to this invention the exterior or interior walls of ships and other 20 floating structures are provided with cavities arranged so that they may be accessible and, if necessary, may be filled in with concrete or any suitable hard setting dense 25 composition in order to strengthen the wall structure at that particular place if damaged or weakened due to any unforeseen cause. These cavities preferably formed between double slabs are separated one from the other by webs and normally are sealed 30 at both their upper and lower ends, but are accessible by removable plugs or the like which may be inserted or built into the concrete preferably at or in close proximity to the upper and lower extremities of each 35 cavity, so that by removing the requisite plug any collected moisture in the cavity may be readily drained off. The webs between the cavities and integral with the walls may be arranged to separate the cavities both in vertical and horizontal directions and, together with the walls are properly reinforced so that the walls thus constructed form, in the true sense, girders or beams adapted to take any lateral loading 45 and readily and effectually to resist any stresses to which they may be subjected.

Moreover, by providing for a suitable communication between the cavities, it is possible to use the latter, if necessary, for 50 water ballast, for instance, in the case of a

double bottom ship where the double bottom is used for that purpose.

The above and other characteristics of this invention will be clearly understood from the following description of the accompanying 60 drawings, in which:—

Figure 1 is a vertical cross section of a vertical wall and adjacent parts of a ship provided with unbroken vertical cavities between the deck and bottom, according to this 65 invention.

Fig. 2 is a similar section in which the vertical cavities are sub-divided into cells.

Fig. 3 is a horizontal section on a somewhat larger scale on the line III—III of 70 Fig. 1.

Fig. 3^a is a fractional section of a known wall structure, showing reinforcements as used hitherto.

Fig. 4 is a vertical section on the line 75 IV—IV of Fig. 3, and

Fig. 5 is a partial longitudinal section on the line V—V of Fig. 3.

Similar reference numerals have been chosen to designate the same or like parts 80 throughout the drawings.

1 is the deck of the ship, 2 is the outer skin, and 3 the inner skin of the vertical wall produced by the provision therein of the vertical cavities 4.

As shown, each vertical cavity 4 is accessible at its upper end from the deck 1 by way of a vertical hole 5. 6 is a lateral hole in the inner skin 3 giving access from the hold of the ship. The hole 5 is normally 90 sealed either by a wooden block or plug not shown or by a poor quality concrete or any other dense setting material which, if desired or necessary, may be easily knocked out and replaced. 7 is a hole at the bottom 95 of the cavity forming connection between the cavity 4 and the bottom 16 of the ship. 8 is a lateral access hole in the skin 3 between the cavity 4 and the hold of the ship. The hole 7 is preferably smaller than either 100 the holes 5 or 6, but the number of the holes 7 may be greater than the number of either the holes 5 or 6 so that the total area of the holes 7 need not be less than the total area of either the holes 5 or 6. The hole 8 would 105 probably not be formed in the wall, but it is a possible hole in the case of a separate drainage system for cavity walls, in which case the hole 7 would be normally plugged up. For instance, where a double bottom 110

shown connected by ribs 17, is used for water ballast, it might be considered inadvisable to utilize the cavities 4 for water ballast, and, in this case it would be possible, but not desirable, to have the passage 7 open between the cavity 4 and the bottom of the ship.

Another way of insuring that the cavity 4 would not be liable to be filled with water when the double bottom is pumped full 10 would be to omit or plug up the hole 6 and, of course, the hole 5, in which case even if the hole 7 were open the respective cavity 4 could not be filled with water as there would be no escape for the air. This probably would be the best method of preventing the cavity 4 from being filled with water and at the same time giving drainage from the cavity into the bottom of the ship where it would be more convenient for any drainage 20 water to be pumped out. If it is desired to utilize the cavity 4 for water ballast, each hole 7 is unplugged, the hole 8 plugged and the hole 6 freed to allow the passage of air.

As will be seen, in the case of any damage 25 to either the outer skin or section 2 or the inner skin 3 of the wall, the access hole 5 leading from the deck to the cavity 4 between the damaged parts would be unplugged and the cavity 4 filled with either 30 concrete or any other hard setting dense composition. The hole 5 being larger than each of the holes 7, the largest aggregate of the concrete which would pass through the hole 5 would be too large to pass through 35 the hole 7 and would effectually jam the holes 7. Thus, while it is possible to use the cavities 4, if necessary, for water ballast, yet, in the case of any damage to the wall of the ship due to collisions or other 40 causes, these cavities are employed to enable an immediate repair to be effected therein.

In the arrangement shown in Fig. 2, the vertical cavities 4 shown in Fig. 1 are subdivided or split up by horizontal webs 9 45 into smaller vertical cavities or cells. Like the vertical webs 11 which separate the cavities 4 vertically one from the other, the horizontal webs 9 may be of any requisite or desired number. 10 designates relatively large 50 holes in the webs 9 to permit drainage between the individual cells and, if necessary, to permit of the filling of any or all of the cells in a row from the deck of the ship to provide for easy and immediate repair.

55 As shown in Figs. 3, 4 and 5, the webs between the cavities and the skins or slab sections connected by these webs are reinforced by vertical bars 12 arranged equidistant throughout and centrally in the inner and outer slabs and by horizontal bars 13 and 14 which are placed one on each side of the vertical bars, as clearly shown in Fig. 4. In a concrete ship the shearing stresses on the walls due to longitudinal wave action 60 are thus taken up by the reinforcement in

the slabs provided by the net work of the bars 12, 13 and 14, and the bars 13 and 14 act as reinforcement for the slabs 2 and 3 when acting as horizontal beams between the webs 11.

70 The reinforcement of the webs 11 is constituted by cross bars 15 of the shape clearly shown in Fig. 3. These cross bars are, as shown, each provided with an angular or oblique center piece and with lateral members 15' extending parallel from the opposite ends of the center-piece in opposite directions and provided with inwardly bent ends or anchoring lugs 15'' adapted to be anchored in opposite directions about one of the vertical bars 12 in each slab section. The effect of these cross bars 15 is that the junctions between the webs 11 and the walls 2 and 3 are reinforced at the corners and, therefore, the parts 2, 3 and 11 reinforced 80 as shown and working in conjunction, constitute in reality a horizontal frame girder as clearly seen in Fig. 3 such that if an accidental concentration of loading is applied at any point of the boat a considerable horizontal distributing effect is created by this arrangement.

85 By virtue of the vertical webs 11, moreover, the wall is caused to act as a vertical beam from the deck to the bottom of the ship to take any lateral loading, and the reinforcing bars 12 provide the necessary reinforcement to aid the wall to act in this direction.

90 The advantages of the reinforcement above 100 described will be more readily appreciated from a comparison with Fig. 3^a showing reinforcements as hitherto used in a reinforced concrete ship having a single skin or slab. In this case, as will be seen, the reinforcement 12' is concentrated substantially in two places and that in the single skin 2' in proximity to the junction between the rib or web 11' extends over a width equal to or slightly greater than the width of the web, it being 105 customary to reinforce the remainder of the concrete slab 2' only lightly in a vertical direction. The reinforcement 12' not being laterally supported on each side of the web 11' can contribute very little to the horizontal 110 shear which the wall is called upon to resist in rough or wavy water, whereas the reinforcing bars 12, shown in Fig. 3, due to their lateral support all contribute to counteract such horizontal shearing stresses. 115 Owing to this fact and to the arrangement shown, it is possible to use actually less weight of steel in cavitated walls arranged according to this invention than in the single skin type. The thickness of the slab 125 forming the outer wall of a ship is determined by considerations of shear under wave action so that the combined thickness of the inner and outer skins 2 and 3 need not exceed the thickness of the single skin 2' and 130

therefore the double skins need not, in fact, be heavier than the single skin.

In the case of single skin ships, moreover, the thickness of the webs 11' is more frequently governed by the mechanical requirements for its reinforcement 12' and not by considerations of shearing stresses and since in a double skin body the thickness of the webs 11 is governed solely by considerations of shear, it will usually be found that the webs 11 may be made very much thinner than the webs 11'. Also to obtain the same horizontal distributive effect of a double skin wall would in a single skin body be possible only by providing closely spaced horizontal stringers or webs in addition to the main webs 11' which would obviously result in a considerable increase of the total weight of the boat.

20 In effecting steel reinforcements as hereinbefore described it is advisable in forming the joints in the reinforcing bars to combine the process of lapping and welding so as to form weld and lap joints in an appropriate 25 staggered relation to one another.

Assuming, for example, a bar 30 feet long lapped 3 feet, the percentage of efficiency of the total weight of steel is roughly 27/30ths or equal to 90%. If the bars were only 30 butted and welded about 80% of strength of the bars could be relied on at the joint. By the combination, however, of overlapping and welding the efficiency of 90% due to the overlapping plus 80% of the 10% 35 due to the welding and which would have otherwise been wasted, is obtained, giving a total percentage of efficiency of 98%. In other words, the usual method of overlapping is employed and, in addition, the ends 40 of the bars are welded.

Of course, the shape or configuration of the cavities could easily be varied as well as

the angular arrangement or position of the webs according to particular requirements without affecting the spirit of the invention 45 and it is therefore obvious that this invention should not be held limited to any of the constructional forms hereinbefore specifically referred to for various modifications would readily be conceived by those skilled 50 in the art without departing from the chief characteristics thereof.

What I claim and desire to protect by Letters Patent is:—

1. A reinforced concrete floating structure 55 having walls with vertical cavities side by side and superposed, ports in the deck, one for each group of superposed cavities; said superposed cavities being in communication with each other, substantially as described. 60

2. A reinforced concrete floating structure having vertical cavities in its walls the bottoms of which have openings communicating with an adjoining space and openings at the upper ends of said cavities of larger size 65 than the bottom openings, substantially as described.

3. A reinforced concrete floating structure having cavities in its walls with ports for the access to each individual cavity both from 70 the deck and laterally from the hold at the ends of a cavity, the port in the bottom of the lowest cavity of each vertical series being smaller than the corresponding deck hole so as to enable the filling material introduced 75 through the deck hole to jam the said bottom hole in filling the cavity.

In testimony whereof I have affixed my signature in presence of two witnesses.

EVAN OWEN WILLIAMS.
